(57) **CLAIM**

The ornamental design for a remote control device for a camera, as shown and described.

DESCRIPTION

FIG. 1 is a top plan view of a remote control device for a camera showing a first embodiment of my new design.

FIG. 2 is a bottom plan view of the remote control device of FIG. 1.

FIG. 3 is a front view of the remote control device of FIG. 1.

FIG. 4 is a rear view of the remote control device of FIG. 1.

FIG. 5 is a right side view of the remote control device of FIG. 1.

FIG. 6 is a left side view of the remote control device of FIG. 1; and,

FIG. 7 is a perspective view of the remote control device of FIG. 1.

The broken line showing of a connection cord and connector in FIGS. 1-3 and 5-7 is for illustrative purposes only and forms no part of the claimed design.
